OPERATING PHONOGRAPH OVER
COMMUNICATION CIRCUITS

Harry R. Van Deventer, New York, N. Y.

Application January 15, 1944, Serial No. 518,346

48 Claims.

(Cl. 179—6)

This invention relates to operating phonographs over communication circuits, and has for an object the provision of means operable over such circuits for connecting a phonograph thereto and either supplying via the circuit the necessary current for directly operating the phonograph motor, or (if a spring-wound motor or the like is used) supplying current via said circuit to wind the spring motor.

Another object is to provide circuits and instrumentalities in combination that will enable phonographs to be connected to lines terminating in the usual exchange equipment wherein the motors for the phonographs can be operated by current from a source located at the exchange and supplied the phonograph motor via the cord circuits in the exchange when same are connected to the line circuit.

A further object is to provide circuits and instrumentalities in combination, that will enable a telephone and phonograph to be operated conjointly on the same line circuit when connected to the exchange equipment now in common use, and where the motor for operating the phonograph is energized by current supplied via the telephone line.

Other objects will be apparent from the following specification wherein by way of illustration preferred embodiments of the invention are disclosed. It will be apparent however that once the inventive concept herein disclosed is understood, many modifications will be apparent; their illustrations therefore are not to be considered as limitative but as defined in the appended claims.

It will be understood that by the term "communication circuit" is meant a circuit, such as a telephone circuit or any other circuit over which speech or signals are transmitted, and over which such signals and operating current for the phonographs may be separately or simultaneously transmitted. Such lines have certain normal characteristics which might be interfered with by the disturbances created by the phonograph motors connected thereto. Therefore, means are herein disclosed for filtering out such disturbances by means of filters connected to the motors and the circuits whereby the normal characteristics of the circuits are preserved.

In the accompanying figures:

Figure 9 is a diagram of the circuit connections of a telephone instrument and phonograph combination embodying the invention.

20 In the prior U. S. Patent Number 2,332,359, dated October 19, 1943, and U. S. application Serial Number 509,544, and filed on November 9, 1943, are shown phonographs that may be connected to telephone lines to transmit and record speech thereover. As shown in this patent and application, the phonographs are operated by

25 motors connected to a local source of current, such as the electric lighting circuit on the subscriber's premises where the phonograph is located usually adjacent the subscriber's telephone. With such an arrangement the operation of the device is dependent upon the current supply which is often not under the control of the telephone company who furnishes the phonograph equipment.

30 In many cases where it is desired to use phonographs on telephone lines, no electric current is available. This is especially true in isolated rural communities. With the system herein disclosed the phonographs are operated by current that may be supplied over the telephone lines, thus placing all of the apparatus and the current supply therefor under the control of the telephone company.

45 It will be understood that the telephone line wires L1, L2 in the figures may connect to the usual central office equipment in common use. Such equipment in the case of a so-called "common battery" system includes the usual line and cut-off relay, line lamp, jacks, etc., all of which

50 may be of any desired and known type. Such offices have switchboard cord circuits for connecting the various lines, and these may be of any known type, it being one of the objects of this 55 invention to provide circuits and instrumentalities

ties for use at the telephones and phonographs which will require very slight, if any, changes in the central office equipment. Line and cord circuits are shown in Patent Number 2,332,359 hereinafter mentioned.

In Figure 1 the numeral 10 denotes within the dotted lines a conventional telephone instrument having a signal device such as ringer S, a condenser C, receiver R, transmitter T, hook switch H, and induction coil I. The hook switch H is moved from normal open circuit position to closed circuit position by an arm 11 shown diagrammatically in the figure as operated by a cam 12, driven by the phonograph motor 13, which also operates the record table 14, carrying record 15, which when contacting reproducer 16, produces sound which issuing from 16, impinges upon the adjacent transmitter T, and is transmitted over line L1, L2, in the usual manner. Thus the phonograph is operatively connected to the circuit L1, L2.

The phonograph motor generally denoted by the numeral 13 is of any desired type, and as shown diagrammatically drives the record table 14 at any desired speed. The shaft of this motor makes a predetermined number of revolutions during which cam 12 operates arm 11, the cam being geared or otherwise suitably driven. As the details of construction of such devices are well known, they are not herein shown in detail, and in the Figures 2, 3 and 4, the motor, turntable, record, reproducer and other parts, as shown in Figure 1, are diagrammatically shown at 13 as a motor winding only, for the sake of simplicity.

The foregoing briefly describes an acoustically coupled telephone-phonograph combination as more fully described in copending application before mentioned, and such a combination can be used with any of the circuits herein described. Should it be desired to use an electric phonograph, then the circuits of same are shown in Patent Number 2,332,359 hereinbefore mentioned, and such electric phonographs may be used with any of the circuits shown herein.

Adverting to Figure 1, the numeral 17 denotes the means for connecting the phonograph and its motor to the line circuit L1, L2. This may be a suitable relay responsive to ordinary ringing current, or it may comprise contacts on the ringer S of the telephone instrument as shown in the Patent Number 2,332,359 aforesaid, or mechanism moved by the ringer armature as shown in the application aforesaid. It is sufficient to state here that the means 17 is responsive to alternating current, the condenser 18 in series therewith making it opaque to direct current.

An operator impressing ringing current on line L1, L2 will operate the means 17, which closes contacts 19, as long as energized. This establishes a path for current from line L1 via conductor 20, through the winding of motor 13, via conductor 21, through contacts 19, through manual switch 22 to L2. This will cause a slight operation of the motor 13.

The operator rings several times on the line, or if the machine ringing is used, the means 17 will be operated a number of times—say four, for a period of say one and one-half seconds "on" and one and one-half seconds "off" each time.

Each time the device 17 operates it closes a circuit through motor 13, and each operation of the motor 13 moves cam 12 driven thereby until arm 11, resting on this cam, is raised sufficiently to close contact 23 to complete a circuit around contacts 19, so that the motor 13 will now oper-

ate continuously throughout its cycle, operating on the current flowing over line L1, L2 from the central office battery until cam 12 drops arm 11 to open contact 23, whereupon the motor stops.

As soon as contact 23 is closed thereby connecting motor 13 across the line L1, L2, the supervisory signal in the operator's cord is extinguished in the usual manner; this is also brought about by the operation of arm 11 connecting the telephone to the line, which telephone is also disconnected when arm 11 is in the non-operating or "at rest" position shown in the figure.

From the foregoing it will be seen that the operations performed by the operator, when calling on a telephone line equipped with a phonograph, do not differ in any way than when calling on a line not so equipped, and that the phonograph instrument at the subscriber's station is entirely free from any connection with the local electric light circuits or any other source of current, except that obtained over the line wires L1, L2.

The operation can only start the phonograph if the subscriber has closed switch 22 and once the contact 23 has closed, the operator cannot stop the phonograph, which must then complete its cycle, the record 15 being revolved sufficiently to deliver the desired message while cam 12 makes one revolution.

Should it be desired to have the operator stop as well as start the phonograph—often desirable when recording—the arrangement shown in Figure 2 may be used, and the control means 24 is any suitable form of step-by-step or "off" and "on" relay which, on receiving an impulse of current, will close contacts 25, and on the next impulse, will open them. Here assuming the switch 22 to be closed, upon the operator ringing on line L, L, the device 24 will close its contacts 25, thereby establishing a circuit from L1 via conductor 20 through winding 13 of the phonograph motor, through contacts 25 and contacts 26 via conductor 27 and switch 22 to L2. This starts the phonograph which continues to run until the operator again rings on the line L, L, and operates the device 24 to move its contacts 25 to open or "off" position.

Should the record 15 become exhausted so that the recorder or reproducer arm 28 must be reset, the contacts 25 are broken when the arm reaches the end of the record and the phonograph is thereby stopped and will remain inoperative until arm 28 is reset. As soon as it is moved, if the device 24 is in the "on" position, the motor 13 will begin to operate, but the subscriber can prevent this by manually resetting the device 24 by pressing the usual reset button 29. As the construction of such step-by-step relays are well known, the device 24 is not here described in detail.

The operation of the telephone instrument in connection with Figure 2 is the same as with Figure 1, except the arm 11a instead of being operated like the arm 11, Figure 1, by a cam on the phonograph motor, may be operated by a magnet 30 which is always energized when the phonograph is in operation. Thus with the arrangement shown in Figure 2, the operator can start and stop the phonograph, the motor of which is operated by current flowing over the line L1, L2.

The circuit, Figure 2, obviously cannot be used with machine ringing, for successive applications of ringing current would cause the device 24 to alternately open and close its contacts, but may be used where manual ringing is employed and the operator is instructed to ring one long ring on phonograph-equipped lines.

The circuits and apparatus shown in Figure 3 may be used with either manual or machine ringing. Here the relay 31 has a winding 31a in series with condenser 18 across the line L1, L2, and a locking winding 31b also across the line in series with the motor 13, the normally open contacts 32 and the lower contact 33 of the cam arm 11. When the operator rings on the line (switch 22 being closed), relay 31 closes contacts 32 and the line current flows through the motor 13, winding 31b and the lower contact 33, holding the relay contacts 32 closed. This starts the motor, revolving cam 12 and raising arm 11 from contact 33 which opens the circuit through winding 31b of relay 31 which releases its contacts 32. As 33 breaks contact with arm 11, the latter closes contact 34 which maintains the circuit from L1 to L2 through the motor windings 13, and the motor continues to operate until cam 12 moves arm 11 to open contact 34.

The operation of the telephone hook switch H is as previously described in connection with Figure 1.

In Figure 4 is shown a circuit embodying a time-delay relay of any suitable type which closes immediately upon application of current thereto, but remains closed whether further energized or not for some predetermined time—say thirty seconds during which time the phonograph may either deliver or record a message.

In this figure the relay 35 has an armature or moving member 36 attached to a dash-pot or other known time-delay device 37. As many such relays are known, the showing here is diagrammatic. This relay will, when energized by the operator ringing on the line, close contact 38 thereby establishing a circuit through the motor winding 13 and supplying same with current from lines L1, L2.

The telephone hook switch H is operated as previously described in connection with Figure 1.

The circuits previously described show apparatus for use on ordinary common battery telephone lines where the usual common battery voltages and amperage is available at the telephone for operating the phonograph motors 13, which only operate when the phonographs are actually in use.

As the phonograph motors are connected to the talking circuits while the latter are in use, some motor noise may occur unless noise suppressors commonly termed "filters" are applied. These may be placed in any of the circuits herein described and are shown in Figure 4 where 39, 40 denote suitable choke coils in the motor circuit which may in addition have the condenser 41 therein as shown. Any other suitable filtering or noise-suppressing means may be employed to prevent the operation of the motor from affecting the talking circuits.

In some installations it may be desirable to employ a higher voltage to the telephone lines than that usually available in telephone exchanges in order to supply suitable current to the phonograph motors, and this may be accomplished with a minimum change in the central office equipment by the arrangement shown in Figure 5. Here a switch key 42 is connected as shown so that normally the regular exchange battery 43 is connected to plug 44. When key 42 is operated, it substitutes the higher voltage battery 45 with its attendant relays etc., for the regular battery 43. The relays or repeating coils associated with battery 45 are suitable for use with the voltage of said battery. The supervisory

lamp 46 is not switched by key 42, but when the latter is operated, a resistance 47 is placed in series with the lamp to compensate for the increased voltage. No attempt is made in Figure 5 to show any details of the cord circuit, operators telephone, etc., as these do not relate to the inventive concept disclosed in this figure, and their arrangement may be varied within wide limits.

The busy test is preserved on lines in which plugs such as 44 are used, as the resistance 47R preserves the continuity of the sleeve circuit S of the plug through the lamp 46 with relay 46R in any position. Resistance 47 merely protects the lamp 46 from the increased voltage when battery 45 is used. Resistance 47R is sufficient to totally extinguish the lamp 46 while preserving the continuity of the sleeve circuit for busy test purposes.

In the case of magneto exchanges and where the telephones are of the local battery type, the provision of special cord circuits like Figure 5 with the usual bridged supervisory ring down drop 48 in series with a condenser 49 across the cord will enable any of the circuits Figures 1 to 4 inclusive to be operated. For magneto exchanges the supervisory lamp 46, resistance 47 and the accompanying supervisory relay 46R are not required, the latter being replaced by a proper impedance coil. Also when the telephones are for magneto service using hand generators for signalling the exchange it is well to provide the generator 50 with a pushbutton 51, Figure 4, the generator being connected between L1 and the lower contact 52 of this pushbutton so that when signalling central the subscriber will not operate his own phonograph equipment. Such a pushbutton can be applied if a hand generator is used at the telephone to any of the circuits Figures 1, 2, or 3, by slight modifications in the wiring that are obvious.

The expression "cord circuit" used in this specification is meant to include any form of connecting device that can, in a central office, make connections to the communication lines 45 therein, whether through switchboard jacks or in any other manner, the connections being made by the operator at the exchange or by any suitable remote-controlled switching device operable by the subscriber over the communication circuit, as commonly used in so-called automatic exchanges.

It will be observed that in all cases the subscriber can signal the exchange operator while a special cord circuit such as that shown in Figure 5 is in use. In a common battery office, if the subscriber raises and lowers the hook switch H on the telephone, the supervisory signal lamp 46 will flash. In a magneto office, the subscriber operates the magneto generator 50, Figure 4, 60 while pressing the button 51, and thereby operates the signal 48 in the cord circuit. The key 42 may be equipped with a pilot light 53 which is "on" when the key is thrown and "off" when it is restored to normal.

While telephone apparatus is shown in Figures 1 to 5 inclusive, it will be understood that other communication apparatus such as telegraph or facsimile apparatus can be used, the inventive concept being broadly the use of the line circuit for at least two purposes; to wit, as a communication channel and simultaneously therewith supplying via the same channel, the operating current for the phonograph instrument. At times the channel is also used to control the operation of the phonograph; i. e., to connect and

disconnect it from the line circuit. Changes in the instrumentalities such as relays, condensers, etc., necessary when other than telephone apparatus is used are well understood and are therefore not described herein.

In some systems it may be desirable to operate the phonographs by a mechanical motor such as the usual spring motor often used with portable phonographs.

Referring to Figure 6, a mechanical motor—for example a spring motor—is diagrammatically shown at 54. As the construction of such motors is well known, it is not shown in detail. Such motors have a control mechanism for starting and stopping the motor, such as the lever 55 normally held in the "stop" position by spring 56. The motor may have a winding key (not shewn) whereby it may be wound by hand in the usual manner.

A relay 57 is serially included in circuit between line L1, the condenser C, the normally closed contact 58 of push-button 59 (which contact may be in the shunt spring of the hand generator 60 or any other signalling device adapted to send a signalling current out over L1, L2, such contact mechanisms being well known) and the line L2.

When the operator rings on the line, relay 57 attracts its armature 61 normally held if necessary in open position by the spring 62. Armature 61 engages and moves the lever 55 to the "on" position which permits the motor 54 to operate and shaft 63 revolved thereby operates any suitable mechanism such as the gear train 64 to cause cam 65 to release arm 66 to engage contact 67 thereby completing a circuit through battery 68 and winding 69 on relay 57, the armature 61 of which holds the control lever 55 in position while the motor 54 continues to operate the desired length of time determined by the revolution of cam 65.

When cam 65 opens the locking circuit at 67, the armature 61 is released and the control lever 55 released thereby moves to the "off" position and the motor stops. While the motor is at rest, contact 67 is open.

While the motor 54 is in operation, it rotates shaft 70 of the record table 14 as shown in Figure 1 and the phonograph operates as previously described, being operatively connected to the line circuit L1, L2, as the hook switch H of the telephone is permitted to move to closed circuit position by the upward movement of the cam arm 66, which operates in this respect same as the cam arm 11 of Figure 1.

When the subscriber uses the hand generator 60, push button 59 may be pressed to open contact 58 and close contact 71 so that the relay 57 is disabled and will not operate to place the phonograph in service on outgoing calls. If the contacts 58, 59 and 71 are in the hand generator shunt, then the mere act of turning the generator crank will be sufficient and the telephone can be used without the phonograph.

On party lines the control means such as relay 57 may be a Gill selector, or any type of selector relay responsive to code or other impulses, such for example as the relay shown in the copending application Serial Number 456,157, filed on August 26th, 1941, so that the phonograph will respond only when the particular telephone where it is located is called.

Figure 6 shows a magneto telephone and line. If the line is connected to a common battery exchange, the telephone circuits will be modified

accordingly, battery 68 may be omitted and the conductors 72, 73 connected to L1 and L2 respectively. Of course the hand generator 60 and pushbutton 59 are omitted as unnecessary, and condenser C and ringer S are connected in series across the line L1, L2, conductor 74 then being connected to L1.

The foregoing description of Figure 6 presupposes that the phonograph motor 54 is hand wound. If the subscriber fails to wind it periodically, the phonograph will not operate, and it is desirable to have the winding of the phonograph under the control of the central office operator where it can be attended to as a matter of operating routine—say between 2:00 and 3:00 a. m., or at such other time as the telephone line is not liable to be in use. This may be accomplished by the additional equipment now to be described in connection with Figure 6 wherein at 15 75 is shown an electric motor connected by suitable gearing indicated at 76 with the winding wheel 77 of the spring motor 54 having the release pawl 78 which releases the wheel 77 when the spring of the motor 54 is sufficiently wound. 20 Such electric-spring combinations are in common use on home phonographs.

By applying current to motor 75 it will wind the spring in 54, and may be so designed as to require a very small current for its operation. It may be designed to operate for a period of forty-five minutes to wind the spring in 54 sufficiently to permit the phonograph to deliver or record sufficient messages so that it need not be wound but once in 24 hours, and as this winding is done 25 when the telephone or phonograph is not in use, there is no danger of motor-noise interfering with the transmission over line L1, L2.

The motor 75 is connected across lines L1, L2, in series with contacts 79 of a relay 80 having a winding 81 in series with a condenser 82, contacts 58, 59 and lines L1, L2 as shown. To operate motor 75, the operator rings on line L1, L2 in the usual manner, using some other frequency than is used to operate ringer S. For example, if 16 cycle current is used for the ringer S, the relay 40 80 may be operated by 66 cycle current. This obviates starting the phonograph when operating motor 75.

When relay 80 closes its contacts, a holding or 50 locking circuit is established for direct current from L1 over conductor 82 to the cam arm 83, contact 84 locking winding 85 and contact 86 to L2. This holds relay 80 closed until cam 87 operates to open contact 84. Cam 87 is connected to the gearing 76 in any suitable manner and forms 55 a second control device, so that when it operates, the holding circuit remains closed long enough for motor 75, which is operating the while, to fully wind the spring of motor 54. The pawl 78 permits the motor 75 to overrun should the spring be partially wound when the motor 75 starts. The motors 54 and 75 together form a "motor means" for operating the phonograph.

When relay 80 is released, it opens the circuit 60 through motor 75 as well as through its own holding coil 85 and the winding apparatus (motor 75) is disconnected from the line circuit.

In some installations the condenser 82, Figure 6, may be omitted and the conductor 98 connected to condenser C at 96 thereby using only one condenser C. Also, the battery 68 may be the telephone battery shown at B. Also, when operating this circuit, the operator can use say 16 cycle ringing current to operate the telephone 70 75 ringer S so as not to operate relays 57 and 80.

Relay 57 may then be operated by 33 cycle current and 80 by 66 cycle current. By this means the operator has independent control of the telephone and phonograph and of winding the latter.

The operator's cord circuit to supply current to the line for operating motor 75 may have a supervisory signal in series with the current source to indicate when the winding operation is completed. This is shown in Figure 7 where 88 is a suitable source of current for the motor 75, and 89 is a supervisory relay controlling the pilot lamp 90 which is illuminated as long as the plug 91 is connected to a line and a motor 75 is in operation thereon.

The subscriber can signal the central office when the cord circuit, Figure 7, is in use. This may be accomplished by providing relay 88 with an armature 92 which will not close when armature 93 closes, but will only close when the subscriber removes his receiver R from the hook H, thereby increasing the current flowing through relay 88. Lamp 94 will then be illuminated and by moving the hook up and down, the subscriber can attract the attention of the operator.

Another method whereby the subscriber can signal the operator is to operate the pushbutton 59, Figure 6, thereby opening the circuit through the motor 75 and flashing lamp 90 to attract the operator's attention. Thus the motors 75 can be wound without making it impossible for the subscriber to get the operator the while.

Figure 8 illustrates an arrangement whereby when the spring wound motor 54 requires rewinding it will automatically connect the electric motor 75 to the line, wind itself and restore the circuits to normal. This is accomplished by mounting a contact device such as the cam 97 to be driven by the gear train 63 on motor 54 in such a manner that the cam will make one revolution with one winding of the spring of motor 54. When the motor spring is about exhausted; that is to say, when it should be rewound, the lobe 98 of cam 97 operates the contact 99 bridged across the contacts 86 of relay 80. This causes relay 80 to close its contacts thereby starting motor 75 as described in connection with Figure 6. Lobe 98 may pass by the contacts 99 but as relay 80 locks in, the motor 75 will operate until cam 87 driven by the winding gear train 76 (shown in Figure 6 and indicated by dotted lines, Figure 8) operates to break the normally closed contact 84 thereby releasing the relay 80 by opening the circuit through locking winding 85 thereof, thereby opening the motor circuit at 79. The phonograph motor 75 will not be running while this winding operation is taking place. If it should be running when the winding operation starts, it will complete its cycle and stop before the motor 75 completes its cycle, therefore as motor 75 will be across the line L1, L2 the operator's supervisory signal on that line will be extinguished long after the supervisory signal on the other end of the cord in use is lit. The operator will therefore listen in on L1, L2 and will know the motor 75 is operating because of a tone signal impressed on the line by the interrupter 100 in series with devices such as the centrifugally operated switches 101 and 102, and a resistance impedance or repeating coil winding 103. The operator therefore knows when listening on the line, that a phonograph is being wound, and may leave the plug up on the line until the winding is completed whereupon the circuit L1, L2 being restored to normal when cam 87 operates, the

supervisory lamp will light and the operator may take down the plug.

The tone-signal will not be heard on the line should the phonograph operate as the circuit is opened at 102 when the phonograph shaft 63 is rotating. The circuit is open at 101 when the motor 75 is not operating, so when the operator rings on the line, operating relay 57 and the phonograph as previously described in connection with Figure 6, the tone circuit is inoperative.

Figure 8 is in all respects not specifically described, same as Figure 6. If used on magneto lines, some local source of current must be available if the automatic self-winding feature just described is desired. This may be a connection to the local lighting circuit or a suitable battery connected at 104, 105, the wires 82 and L2—1 being cut as shown at x. In the event this is done, the tone circuit may be completed to L1, L2 inductively by winding 106 on the same core as the tone signal winding 103 and therefore coupled thereto. The condenser 107 makes this circuit opaque to direct current.

The details of construction of the phonograph instrument per se are not described, as it is obvious that the phonograph can be used for recording or reproducing or both; that is to say, if equipped with a talk-out record it will first deliver a message before recording one. Such a phonograph instrument is described in detail in Patent Number 2,261,420 dated November 4, 1941, and as the instant application is limited to the circuits and instrumentalities necessary to control the phonograph, the construction of the latter is not described in detail.

Therefore the phonograph may be termed a "sound device" and is so referred to in some of the appended claims, this term defining a phonograph that will record or reproduce or both.

Also in the claims, the telephone instrument of any character may be referred to as a "sub-set". Also, it will be obvious, as shown in Figure 9, that without departing from the spirit of the invention herein disclosed, the phonograph mechanism may be completely divorced from the telephone sub-set or other transmitting device.

In Figure 9, by way of illustrating a transmitting device associated directly with the phonograph, the numeral 108 denotes a complete sub-set of any suitable type such as shown at 10, Figure 1. The phonograph equipment is the same as shown in Figure 1, except that the arm 11 operates a switch 109 instead of operating the switch hook H of the sub-set. This places a transmitting device such as the transmitter 110 across the line L1, L2, instead of the transmitter T, Figure 1. In all other respects the operation of the apparatus, Figure 10, is the same as that shown in the preceding figures.

Should the circuit L1, L2 be a magneto line, the transmitter 110 would be provided with a local battery and connected to the line via an induction coil in the usual manner, as shown diagrammatically between the dotted lines 111.

The device between the dotted lines 112 may therefore form a unit adapted to be connected to a line circuit and operated independently of any other device such as the telephone 108 connected thereto, and in accordance with the circuit arrangement shown in any of the preceding figures.

What is claimed is:

1. A communication circuit, a telephone transmitter connected thereto, a phonograph including an electric motor, means operable over said

circuit for connecting said phonograph and motor thereto and a source of current connected to said circuit for continuously operating said motor while same is connected to said circuit.

2. A communication circuit, a telephone transmitter connected thereto, a phonograph including an electric motor, means operable over said circuit for connecting said phonograph and motor thereto and a source of current connected to said circuit for continuously operating said motor and said transmitter while same are respectively connected to said circuit.

3. A communication circuit, a telephone transmitter connected thereto, a phonograph including an electric motor, means operable over said circuit for connecting said phonograph and motor thereto, a source of current connected to said circuit for continuously operating said motor while same is connected to said circuit, and means controlled by a predetermined number of revolutions of said motor for disconnecting same from said circuit.

4. A communication circuit, a telephone transmitter connected thereto, a phonograph including an electric motor and having a record and translating means therefor, means operable over said circuit for connecting said phonograph and said motor thereto, a source of current connected to said circuit for continuously operating said motor while same is connected to said circuit, and means dependent upon the relative position of said record and said translating means for disconnecting said motor from said circuit.

5. A communication circuit, a telephone transmitter connected thereto, a phonograph including an electric motor, means operable over said circuit for connecting said phonograph and motor thereto and for disconnecting said phonograph and motor therefrom, and a source of current connected to said circuit for continuously operating said motor while the same is connected to said circuit.

6. A communication circuit, a telephone transmitter connected thereto, a phonograph including a motor, means responsive to alternating current flowing in said circuit including a relay having a winding connected thereto, a second winding on said relay, a normally open contact adapted to be actuated by the operation of said relay and in series with said second winding, a phonograph having a motor winding in series with said second winding on said relay and said circuit, switching means operated by said motor for opening the circuit through said second winding of said relay and re-establishing said circuit to place said motor winding directly across said circuit, said means being operable by a predetermined number of revolutions of said motor for opening said last re-established circuit.

7. A communication circuit, a telephone transmitter connected thereto, a phonograph including an electric motor, means operable over said circuit for connecting said phonograph and motor thereto and a source of current connected to said circuit for continuously operating said motor while same is connected to said circuit, said means including a time delay device whereby the length of time said phonograph and motor are in operation is predetermined.

8. A communication circuit, a telephone transmitter connected thereto, a phonograph including a motor, means operable over said circuit for connecting said phonograph and motor thereto, a source of current connected to said circuit for operating said motor, and filter means connected

to said motor and said circuit to prevent electrical disturbances caused by the operation of said motor from affecting the normal communication characteristics of said circuit.

5 9. In combination, a communication circuit, an operator's cord circuit, a phonograph, a motor for driving said phonograph, means connected to said communication circuit and under control of said cord circuit for connecting said motor to said 10 communication circuit and means for operating said motor including a source of current supplied to said communication circuit via said cord circuit.

10 10. The combination as claimed in claim 9 wherein said first means includes a device responsive to alternating current supplied via said cord circuit.

15 11. The combination as claimed in claim 9 wherein the application of said source of current also supplies a communication device connected to said communication circuit.

20 12. In a communication system having a common battery for supplying communication instruments with operating current, connecting 25 cord circuits, lines having communication devices connected thereto and adapted to be connected by said cord circuits, phonographs having motors, means associated with said phonographs whereby current applied thereto via said cord circuits and lines will connect said motors to said lines, and switching means in said cord circuits for connecting a second common battery to said lines to supply the motors connected thereto with operating current.

30 35 13. In a communication system having a central office switchboard including a connecting cord circuit, a line having a communication instrument connected thereto and adapted to be connected to said cord circuit, a phonograph having a motor, means associated with said phonograph whereby current applied thereto via said cord circuit and line will connect said motor to said line, and means for supplying current to said 40 cord circuit for operating said motor.

45 14. The combination as claimed in claim 13 wherein said last means includes the winding of a supervisory device connected to the cord circuit.

15 50 15. The combination as claimed in claim 13 wherein said last means includes a switching device having a supervisory pilot signal operated thereby to indicate when said cord circuit is connected to supply current to said motors.

55 16. A communication circuit, a sound device including a mechanical motor, control means connected to and operable by current flowing in said circuit for starting and stopping said motor, and means operated by said motor to cause said control means to stop said motor after a predetermined number of revolutions thereof.

60 17. A communication circuit, a sound device including a spring motor, control means including an electrical device having a winding connected to said circuit and adapted to be energized by current flowing therein, a second winding on said electrical device serially included in a circuit including a source of current and a normally closed contact adapted to be opened by the operation of said motor, and means controlled by said electrical device for starting and stopping said motor.

65 70 18. A communication circuit, a sound device including a spring motor, control means including an electrical device having a winding con-

75

nected to said circuit and adapted to be energized by current flowing therein, a second winding on said electrical device serially included in a circuit including a source of current and a normally closed contact adapted to be opened by the operation of said motor, means controlled by said electrical device for starting and stopping said motor, and a signal device connected to said circuit, said control device being operable by current of such characteristics that said signal device will not be operated thereby.

19. A communication circuit, a sound device including a spring motor, control means including an electrical device having a winding connected to said circuit and adapted to be energized by current flowing therein, a second winding on said electrical device serially included in a circuit including a source of current and a normally closed contact adapted to be opened by the operation of said motor, means controlled by said electrical device for starting and stopping said motor, a transmitting apparatus adapted to be connected and disconnected from said communications circuit by the operation of said motor, a signal device connected to said communications circuit, and means connectable to said circuit for separately operating said control means and said signal device.

20. A communication circuit, transmitting apparatus connected thereto including switching mechanism whereby the transmitting apparatus may be connected to said circuit, a sound device including a mechanical motor, means operated by said motor for operating said switching mechanism, a control device connected to said circuit and arranged to cause said motor to operate said sound device, means controlled by the operation of said motor for actuating said control device to stop said motor in timed relation to the operation of said first means, means operable to send a signalling current out over said circuit, and switching means associated with said last means for preventing current therefrom from operating said control device.

21. A circuit, a phonograph including a spring motor, means operable over said circuit for connecting said phonograph thereto, an electric motor connected to said spring motor to wind the spring thereof, and control means for operating said electric motor by current supplied thereto over said circuit.

22. The combination as claimed in claim 21 wherein said control means includes a relay connected to said circuit and operable by current flowing therein.

23. The combination as claimed in claim 21 wherein said control means includes a relay operable by current flowing in said circuit and having a locking winding operable by another current flowing in said circuit, contacts in circuit with said winding, and a second control device connected to said locking winding and operated by said electric motor.

24. A circuit, a sound device including a spring motor, means for operatively connecting said device to said circuit, an electric motor connected to said spring motor to wind the spring thereof, control means for connecting said electric motor to said circuit to be operated by current flowing therein, said means including a relay operable by current flowing in said circuit, a locking circuit including a winding and contacts on said relay, and a second control means connected to said

locking circuit for disconnecting said electric motor and operated thereby.

25. A circuit, a sound device including a spring motor, means for operatively connecting said device to said circuit, an electric motor connected to said spring motor to wind the spring thereof, gearing between said motors including an overrun device, control means for connecting said electric motor to said circuit to be operated by current flowing therein, and a second control means for disconnecting said electric motor operated thereby.

26. A circuit, a sound device including a spring motor, means for operatively connecting said device to said circuit, an electric motor connected to said spring motor to wind the spring thereof, gearing between said motors including an overrun device, control means for connecting said electric motor to said circuit to be operated by current flowing therein, and a second control means operated in timed relation to said electric motor for disconnecting same from said circuit.

27. A circuit, a sound device including a spring motor, means for operatively connecting said device to said circuit, an electric motor connected to said spring motor to wind the spring thereof, gearing between said motors including an overrun device, control means for connecting said electric motor to said circuit to be operated by current flowing therein, said means including a relay having a winding connected to said circuit, a holding circuit for said relay including a winding thereon and a contact controlled by said relay, and means controlled by said electric motor for disabling said holding circuit to release said relay and thereby disconnect said electric motor from said first circuit.

28. In combination, line circuits each having a transmitting apparatus and an associated phonograph, said line circuits terminating in a central office, motor means at said phonographs for operating same, means located at said phonographs and controllable from said central office for operatively connecting said phonographs to said line circuits, means including switching instrumentalities applicable to any line circuit in said central office for operating said first means and means partly at said phonographs and partly at said central office for supplying current to the motor means at said phonographs from a source of current located at the central office.

29. In combination, line circuits each having a transmitting apparatus and an associated phonograph, said line circuits terminating in a central office, motor means for operating each phonograph, means at each of said phonographs and controllable over the line circuit associated therewith for operatively connecting said phonograph to said line circuit, means at said central office applicable to any line circuit therein for operating said first means, a source of current at said central office, and means at said central office applicable to any line circuit therein for supplying said current thereto and to the motor means connected in circuit therewith.

30. In combination, line circuits each having a transmitting apparatus and an associated phonograph, said line circuits terminating in a central office, motor means for operating each phonograph, means at each of said phonographs and controllable over the line circuit associated therewith for operatively connecting said phonograph to said line circuit, means at said central office applicable to any line circuit therein for operating said first means, a source of current at said

central office, means at said central office applicable to any line circuit therein for supplying said current thereto and to the motor means connected in circuit therewith, and means operated by a predetermined number of revolutions of a part of said motor means for disconnecting said phonograph from its associated line circuit.

31. In combination, line circuits each having a transmitting apparatus and an associated phonograph, said line circuits terminating in a central office, motor means for operating each phonograph, means at each of said phonographs and controllable over the line circuit associated therewith for operatively connecting said phonograph to said line circuit, means at said central office applicable to any line circuit therein for operating said first means, a source of current at said central office, means at said central office applicable to any line circuit therein for supplying said current thereto and to the motor means connected in circuit therewith, and means operated by a predetermined number of revolutions of a part of said motor means for disconnecting said motor means from its associated line circuit.

32. In combination, line circuits each having a transmitting apparatus and an associated phonograph, said line circuits terminating in a central office, motor means for operating each phonograph, means at each of said phonographs and controllable over the line circuit associated therewith for operatively connecting said phonograph to said line circuit, means at said central office applicable to any line circuit therein for operating said first means, a source of current at said central office, means at said central office applicable to any line circuit therein for supplying said current thereto and to the motor means connected in circuit therewith, means operated by a predetermined number of revolutions of a part of said motor means for disconnecting said phonograph from its associated line circuit, and means operated by a predetermined number of revolutions of a part of said motor means for disconnecting said motor means from its associated line circuit.

33. In combination, a line circuit, a transmitting device, a phonograph having a spring motor, means connected to said line circuit and operable by current flowing therein for releasing said spring motor to drive said phonograph, means operated by said spring motor for connecting said transmitting device to said line circuit, an electric motor connected to said spring motor to wind the spring thereof, and means controlled by said spring motor for connecting said electric motor to said line circuit to be operated by current flowing therein.

34. In combination, a line circuit, a transmitting device, a phonograph having a spring motor, means connected to said line circuit and operable by current flowing therein for releasing said spring motor to drive said phonograph, means operated by said spring motor for connecting said transmitting device to said line circuits, an electric motor connected to said spring motor to wind the spring thereof, means controlled by said spring motor for connecting said electric motor to said line circuit to be operated by current flowing therein, and means controlled by said electric motor for disconnecting same from said line circuit.

35. In combination, a line circuit, a transmitting device, a phonograph having a spring motor, means connected to said line circuit and operable by current flowing therein for releasing said

5 spring motor to drive said phonograph, means operated by said spring motor for connecting said transmitting device to said line circuit, an electric motor connected to said spring motor to wind the spring thereof, and means connected to said line circuit and operable by current flowing thereto for connecting said electric motor to said line circuit whereby said motor is operated by current flowing over said circuit.

10 36. In combination, a line circuit, a transmitting device, a phonograph having a spring motor, means connected to said line circuit and operable by current flowing therein for releasing said spring motor to drive said phonograph, means operated by said spring motor for connecting said transmitting device to said line circuit, an electric motor connected to said spring motor to wind the spring thereof, means connected to said line circuit and operable by current flowing thereto for connecting said electric motor to said line circuit whereby said motor is operated by current flowing over said circuit, and means controlled by the operation of said electric motor for disconnecting same from said line circuit.

15 37. The combination as claimed in claim 36 wherein the means controlled by the operation of the electric motor for disconnecting same from the line circuit includes a relay having a locking winding in circuit with contacts operated by the movement of the electric motor, said relay having a contact controlling the line circuit through the motor.

20 38. The combination as claimed in claim 36 wherein the means controlled by the operation of the electric motor for disconnecting same from the line circuit includes a relay having a locking winding in circuit with contacts operated by the movement of the electric motor, said relay having a contact controlling the line circuit through the motor, and said relay having a winding connected to said line circuit whereby said relay may be operated by current applied thereto via said line circuit.

25 39. In combination, a line circuit, a transmitting device, a phonograph having a spring motor, means connected to said line circuit and operable by current flowing therein for starting said motor and connecting said transmitting device to said line circuit, an electric motor connected to said spring motor to wind the spring thereof, and means operable when said spring motor is at rest and said electric motor is in operation forming a tone circuit for impressing a signal-tone on said line circuit.

40 40. The combination as claimed in claim 39 wherein said last means includes switches operated by said motors.

45 41. In combination, a line circuit, a transmitting device, a phonograph having a spring motor, means connected to said line circuit and operable by current flowing therein for starting said motor and connecting said transmitting device to said line circuit, an electric motor connected to said spring motor to wind the spring thereof, and means operable when said spring motor is at rest and said electric motor is in operation forming a tone circuit for impressing a signal-tone on said line circuit, said last means including centrifugal switches operated by said motors.

50 42. The combination as claimed in claim 39 wherein said last means include switches operated by said motors and serially included in said tone circuit with an interrupter driven by said electric motor, said tone circuit being coupled to

said line circuit to impress a signal-tone thereon while said electric motor is in operation.

43. The combination as claimed in claim 39 including means for rendering said tone circuit inoperative when said electric motor has wound the spring of said spring motor to a predetermined tension.

44. In combination, a line circuit, a transmitting device, a phonograph having a spring motor, means connected to said line circuit and operable by current flowing therein for starting said motor and connecting said transmitting device to said line circuit, an electric motor connected to said spring motor to wind the spring thereof, means connected to said line circuit for starting said electric motor, and means for impressing a signal tone on said line circuit while said electric motor is operating.

45. In combination, a line circuit, a transmitting device, a phonograph having a spring motor, means connected to said line circuit and operable by current flowing therein for starting said motor and connecting said transmitting device to said line circuit, an electric motor connected to said spring motor to wind the spring thereof, means connected to said line circuit for starting said electric motor, means for impressing a signal tone on said line circuit while said electric motor is operating, and means controlled by said spring motor for disconnecting said signal tone from said line circuit while said spring motor is in operation.

46. In combination, a line circuit, a phonograph having a spring motor, an electric motor

connected to said spring motor to wind the spring thereof, a source of current for operating said electric motor, means controlled by said spring motor for connecting said electric motor to said source of current, and means controlled by said electric motor for disconnecting same from said source of current.

47. In combination, a line circuit, a phonograph having a spring motor, an electric motor connected to said spring motor to wind the spring thereof, a source of current for operating said electric motor, means controlled by said spring motor for connecting said electric motor to said source of current, means connected to and operable by current in said line circuit for connecting said electric motor to said source of current, and means controlled by said electric motor for disconnecting same from said source of current.

48. In combination, a line circuit, a phonograph having a spring motor, an electric motor connected to said spring motor to wind the spring thereof, a source of current for operating said electric motor, means controlled by said spring motor for connecting said electric motor to said source of current, means connected to and operable by current in said line circuit for connecting said electric motor to said source of current including a relay having a winding connected to said line circuit and a locking winding in a locking circuit connected to said source of current, and means controlled by said electric motor for opening said relay and disconnecting said electric motor from said current source.

HARRY R. VAN DEVENTER.
